UNITED STATES PATENT OFFICE

123,248

DESIGN FOR A COMBINED DISPENSING CONTAINER AND ERASER DISPLAY, OR THE LIKE

Russell S. Henderson, Morristown, N. J., assignor to Weldon Roberts Rubber Co., Newark, N. J., a corporation of New Jersey

Application January 31, 1940, Serial No. 89,898

Term of patent 7 years

To all whom it may concern:

Be it known that I, Russell S. Henderson, a citizen of the United States, residing at Mount Kemble Lake, Morristown, county of Morris and State of New Jersey, have invented a new, original, and ornamental Design for a Combined Dispensing Container and Eraser Display, or the Like, of which the following is a specification, reference being had to the accompanying drawing, forming part thereof.

In the drawing:

The figure is a perspective view of the combined dispensing container and eraser display, or the like, showing my new design.

I claim:

The ornamental design for a combined dispensing container and eraser display, or the like, as shown.

RUSSELL S. HENDERSON.
